[57] CLAIM

The ornamental design for a chair, as shown and described.

DESCRIPTION

FIG. 1 is a front elevational view of a chair embodying my new design;

FIG. 2 is a perspective view taken from the top, front and right side thereof;

FIG. 3 is a left side elevational view thereof, the right side elevational view being the mirror image of the left side shown;

FIG. 4 is a top plan view thereof;

FIG. 5 is a rear elevational view thereof;

FIG. 6 is a bottom plan view thereof;

FIG. 7 is a front elevational view of a second embodiment of my new design;

FIG. 8 is a perspective view taken from the top, front and right side thereof;

FIG. 9 is a left side elevational view thereof, the right side elevational view being the mirror image of the left side shown;

FIG. 10 is a top plan view thereof;

FIG. 11 is a rear elevational view thereof; and,

FIG. 12 is a bottom plan view thereof.

The fragmentary broken line representation of cushions in FIGS. 2 and 8 are for the purpose of illustration only and form no part of the claimed design.
